UNITED STATES PATENT OFFICE.

EUGEN SPEIDEL, OF PFORZHEIM, GERMANY, ASSIGNOR TO SPEIDEL CHAIN CO., OF PROVIDENCE, RHODE ISLAND, A FIRM COMPOSED OF FREDERICK SPEIDEL AND EUGEN SPEIDEL, BOTH OF PFORZHEIM, GERMANY.

CHAIN.

Application filed June 1, 1926. Serial No. 112,883.

This invention relates to an improved construction of ornamental chain; and has for its object to provide a chain of this character having a gem-setting link about which an ornamental ring is mounted, which ring is retained on the setting by a bendable connector link having one end fixed to the setting and its free end bent to embrace and lock the ornament in position thereon.

With these and other objects in view, the invention consists of certain novel features of construction, as will be more fully described, and particularly pointed out in the appended claims.

In the accompanying drawings—

Figure 1 is a top view showing my improved type of ring.

Figure 2 is a side elevation of the box-shaped gem-setting link with one end of the connector link attached thereto.

Figure 3 is a perspective view of one of the bendable connector links.

Figure 4 shows one form of ring-shaped ornament which is adapted to be held in position about the gem-setting link.

Figure 5 is a top view of the gem-setting link with the ornament removed.

Figure 6 is a side elevation showing the ring ornament in position on the setting link retained by the bendable connector links.

Figure 7 is the same as Figure 6 and showing the ring ornament and the next adjacent links in section.

Figure 8 is a top view of the assembly shown in Figure 7, partly in section.

Figure 9 is a perspective view of the assembly shown in Figures 6 and 7.

Figure 10 is a side elevation partly in section showing another form of ring ornament and bendable connector link having a contracted middle portion to serve as a bearing for the ring.

Figure 11 is a top view of the construction shown in Figure 10.

It is found in practice in the construction of ornamental chains of this character, of advantage, in many instances to employ ornamental members and connect them to the gem-setting link, which ornamental members may be constructed of celluloid or other material, the finish of which may be affected by soldering heat upon it, and in order to apply these ornaments to the setting link after the connecting parts have

been soldered or otherwise attached together and finished I employ a bendable connecting link which may serve a double purpose, first to secure the ornamental ring or member to the gem-setting link and second, to connect this link to the next adjacent link or links of the chain; and the following is a detailed description of the present embodiment of my invention and showing one means by which these advantageous results may be accomplished:—

With reference to the drawings, 10 designates the gem-setting link which may be of the usual box-setting type having a peripheral band with side walls, in the upper edge of which is set the gem 11 by pressing inwardly the edge 12 of the band about it.

In order to render the setting more attractive, I attach an ornamental member 13 thereto, which in some cases, I form of celluloid and in ring shape, the celluloid being of different colors, and in some cases this ornament is formed of metal and positioned about the gem setting.

In order to secure this ornamental ring in position to the setting without being obliged to apply soldering heat thereto after the ring is positioned, I have provided a pair of bendable connecting links 14 which are soldered to the walls of the setting before the ornamental ring is positioned. This bendable link is also designed to connect the setting link 10 to the next adjacent links 15 of the chain. To accomplish this in a simple and effective way, I have soldered one end 16 of this bendable link to the side wall of the setting link after which I place the ring-shaped ornament 13 in position about the setting link and then pass the free end 17 of the setting links through the next adjacent links of the chain and finally fold this free end into closed position, as best illustrated in Figure 7.

It will be observed that in this case in order to obtain the desired result I form the inner diameter of the ornamental ring 13 larger than the outer diameter of the setting link, and the ends of this bendable connector link are positioned between the ornamental ring and the side walls of the setting link to hold the ring in spaced relation to and separated from the setting.

In some instances, in order to further support and space this ornamental ring on the

setting member, I have provided spacer blocks 18 on opposite sides of this setting link which serve to centralize the ring ornament about the setting member.

5 In some instances, instead of employing a ring 13 which is circular in cross section, I may employ a flat shaped ring 20, as illustrated in Figures 10 and 11 and which may be formed of metal or other desired material.

10 In this particular type of ring I preferably employ a bendable link having its middle portions 22 set inwardly toward each other. This inwardly-extending portion 15 forming a rest as at 23 for the support of this ring 20 so as to permit the ring to be mounted loosely about the setting member and be loosely supported in the bendable links 21.

15 My improved construction of chain renders the same capable of being assembled with ornamental members of celluloid of different colors which would be impossible to be attached thereto if solder heat had to be applied thereto after having been positioned thereon.

20 The links of the chain and the ornaments thereon being assembled and secured in position by a folding operation of the bendable 25 connecting link member.

25 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A chain having a link formed as a gem setting having side walls, a ring-shaped ornament about said setting link, and a bendable connector link having one end fixed to the side wall of said setting link and its free end bent to embrace and lock the ring-shaped ornament in position about said setting. 45

2. A chain having a link formed as a gem setting having side walls, a ring-shaped ornament about said link, bendable connector links, each having one end fixed to opposite side walls of said setting and its free end bent to embrace and lock the ornament in position about said setting, the ends of said connector link being positioned between the ring and setting also serves to space or separate the ring from said setting. 50

55 3. A chain having a gem-setting link with side walls, spacer blocks on said walls, a ring-shaped ornament about said setting link positioned by said spacers, a bendable connector link having one end fixed to the wall of said setting link, its free end after having been passed through the next adjacent link being folded to embrace the ornament and secure it to the setting link, the ends of the connector link extending between the ornament and the setting to assist in spacing and separating the ring from the walls of the setting link. 60

65 In testimony whereof I affix my signature.

EUGEN SPEIDEL.
